Specification for Design.

Patented May 18, 1920.

Application filed February 21, 1920. Serial No. 360,400. Term of patent 14 years.

To all whom it may concern:

Be it known that I, MAURICE LOUIS ALPHONSE AMÉ ALLARD, a subject of the King of Belgium, residing at Akron, Ohio, have invented a new, original, and ornamental Design for a Tire-Tread, of which the following is a specification, reference being had to the accompanying drawing, forming a part hereof.

In this drawing—

Figure 1 is a plan view of a sufficient portion of a tire tread to illustrate the design, and

Fig. 2 is a transverse section on line 2—2 of Fig. 1.

I claim—

The ornamental design for a tire tread as shown.

MAURICE LOUIS ALPHONSE AMÉ ALLARD.
